UNITED STATES PATENT OFFICE.

THOMAS J. MORRIS, OF ST. JOSEPH, MISSOURI.

GATE.

SPECIFICATION forming part of Letters Patent No. 392,281, dated November 6, 1888.

Application filed June 29, 1888. Serial No. 278,534. (No model.)

To all whom it may concern:

Be it known that I, THOMAS J. MORRIS, a citizen of the United States, residing at St. Joseph, in the county of Buchanan and State 5 of Missouri, have invented a new and useful Improvement in Gates, of which the following is a specification.

My invention relates to improvements in gates; and it consists in certain novel features 10 hereinafter described and claimed.

In the annexed drawings, which fully illustrate my invention, Figure 1 is a side view of my improved gate, showing it in its normal position. Fig. 2 is a similar view showing the 15 gate raised. Fig. 3 is a detail perspective view of the latch. Fig. 4 is a top plan view of the gate. Fig. 5 is a detail enlarged view of the rack-bar and lever.

Referring to the drawings, particularly by 20 letter, A designates the hinge post, and B the latch-post set in the ground in the usual or any preferred manner and at the proper distance apart.

The gate C is composed of the rails D and 25 the usual end and central vertical double bars, E E, which are pivoted to the rails at their several points of intersection by means of the pivotal bolts F, as shown. Between the central and end vertical bars I arrange the single 30 vertical braces G G, which are pivoted to the rails by means of the pivoted bolts H. The braces near the opposite ends of the gate are arranged on the opposite sides of the same, so as to secure an equitable distribution of the 35 weight of the gate. These braces give great strength to the gate, and will be found to be very advantageous on farm-gates, as they enable the gate to withstand all shocks caused by the live stock running against them, and 40 also prevent breaking of the gate, usually caused by the animals falling upon the gate in an unsuccessful attempt to jump over it. The breaking of the gate from the cause just mentioned has heretofore been a source of much 45 vexatious trouble and loss to farmers, and by my device it is entirely overcome.

The inner or rear edge of the vertical bar at the free end of the gate, or that end opposite the hinges, is provided with a series of 50 notches, I, having downwardly-inclined bases or lower sides, J, and provided with recesses K in said inclined sides or bases.

L designates a pawl or lever, which is pivoted at an intermediate point of its length to one of the rails of the gate and has its upper end normally engaging one of the notches L, the upper end being provided on its under side or edge with a spur or lug, M, which engages the recess K. The lower portion of the pawl below the pivot is somewhat tapered, as shown, 55 to form a handle, by means of which the lug M is disengaged from the recesses K after the gate is elevated beyond ordinary reach, as would frequently occur in passing the gate over deep snow-drifts. The pawl plays in and 60 is held to the gate by a suitable guard, P, secured to the side of the gate in any convenient manner.

In the inner side of the latch-post I form a recess, Q, having a horizontal shoulder, R, at 70 its lower end, which forms a rest or support for the latch S when the same is in engagement with the gate. This latch S is composed of a single U-shaped metallic rod held in the angle of the recess Q at the rear edge of the 75 shoulder R by means of the staples T T and free to swing in a vertical plane. The rear wall of the recess Q is substantially V-shaped, as shown, thereby providing an inclined rest or support, W, for the latch when it is out of 80 engagement with the gate.

In operation the gate is swung to and fro to open and close it in the usual manner. When the gate is closed, the latch is swung down to fasten the same, the parallel arms of the latch 85 passing on opposite sides of the gate, and thereby preventing the gate from swinging in either direction. When the gate is closed and it is desired to adjust it so that small animals may pass, but larger ones be prevented from passing, the pawl is disengaged from the notches and the free end of the gate raised, as shown in Fig. 2, to the desired height. The pawl is then again allowed to engage one of the notches, and the gate will be held at the 90 height to which it is adjusted. This enables me to readily clear snow-drifts and other obstructions, and also to adjust it so as to prevent and compensate for sagging, as will be readily understood. The gate can be adjusted 95 as desired without any moving of the latch, as it will move vertically between the arms of the same, and consequently no adjustment of the latch is rendered necessary by adjusting

the gate. The recesses in the bases of the notches and the spur on the pawl engaging the same effectually prevent any accidental displacement of the pawl, so that the gate will be firmly maintained in its adjusted position.

My gate is cheap, simple, and efficient, and it is thought unnecessary to enlarge further upon its advantages.

Having described my invention, I claim—

1. The combination of the rails, the end bar having notches in its rear edge and provided with recesses in the bases of said notches, and the pawl pivoted to the gate and having its upper end engaging one of said notches, and 15 provided with a spur engaging the recess in the base of said notch, as set forth.

2. The combination of the gate having an end bar provided with notches in its rear edge, said notches having recesses in their bases, the pawl pivoted to the gate and having its 20 lower end forming a handle and its upper end engaging one of the notches in the end bar, and provided with a spur engaging the recess therein, and a guard secured to the gate and extending across the pawl, as set forth. 25

In testimony that I claim the foregoing as my own I have hereto affixed my signature in presence of two witnesses.

THOMAS J. MORRIS.
